(57) CLAIM

The ornamental design for a bandage pad with embossing pattern, as shown and described.

DESCRIPTION

FIG. 1 is an isometric view of a first embodiment of a bandage pad with embossing pattern of the present invention; and,

FIG. 2 is an isometric view of a second embodiment of a bandage pad with embossing pattern of the present invention.

In the drawings, the broken lines show portions of a bandage that form no part of the claim.
